GRID CONTROLLED RECTIFIER TUBE

Charles P. Smith, Lancaster, Pa., assignor to
Radio Corporation of America, a corporation
of Delaware

Application June 20, 1947, Serial No. 756,054

10 Claims. (Cl. 250—27.5)

1 My invention relates to an electron discharge device and more particularly to a grid controlled gas tube.

Some types of gas-filled and mercury-vapor thyatrons using a directly heated filamentary cathode show large changes in starting voltage characteristic when the phase relationship of the filament voltage and anode voltage is varied through 360 degrees. In tubes of this type, it is desirable to use a filamentary cathode heated by an A-C. voltage circuit. The filamentary cathode is enclosed within a heat shield connected electrically to one end of the filament. Also, the usual procedure is to make the grid and anode circuit returns to the filament transformer center tap. The tube discharge takes place through an opening in the heat shield which due to the variation of its potential with the applied A-C. filament voltage, exerts a "grid-action" on the starting characteristic of the tube. This "grid-action" of the heat shield causes large variations in the amount of anode starting voltage required. Moreover, I have found that the required amount of anode starting voltage varies with a change in the phase relationship between the anode voltage and the filament voltage.

It is, therefore, an object of my invention to provide an electron discharge device of the gas type having improved characteristics.

It is also an object of my invention to provide a controlled gas tube having a fixed anode starting voltage for predetermined voltages impressed on the other electrodes.

It is also an object of my invention to provide a controlled gas tube in which the "grid-action" of the heat shield is minimized.

The novel features which I believe to be characteristic of my invention are set forth with particularity in the appended claims, but the invention itself will best be understood by reference to the following description taken in connection with the accompanying drawing, in which:

Fig. 1 is a view partially in section of a gas control tube according to my invention;

Fig. 2 is a cross-sectional view along sectional line a—a of Fig. 1;

Fig. 3 is a schematic showing of a circuit application incorporating the tube of Fig. 1;

Fig. 4 discloses the relationships of the anode starting voltage to the grid bias voltage of gas control tubes; and

Figs. 5, 6, 7 and 8 disclose sectional views of the several modifications of tube structure, according to my invention.

Fig. 1 discloses a gas control tube having an

envelope 10 closed at one end by a press 12. Mounted on this end of the tube is a base 14 having leads 15 extending therefrom. Within the envelope 10 is a circular anode plate 16 supported by rods 18 which are mounted in a depending glass press 20 from the top of the tube envelope. The supporting rods 18 form conductor leads from the anode 16 to flexible leads 19 leading to the terminal cap 24 mounted on the outer portion of the tube.

The cathode electrode of this tube comprises a filamentary element 26. The cathode filament 26 is preferably in the form of a corrugated ribbon which is wound to form a spiral arrangement. The filament spiral 26 is supported on a ceramic rod 28 with the inner edges of the spiral turns resting on the top of the ceramic rod 28. The ceramic rod 28 is in turn supported horizontally by the side rods 30 and 32 which are mounted in the glass press 12. The ends of the filamentary cathode ribbon are respectively welded at 34 and 36 to the corresponding side rods 30 and 32. Side rods 30 and 32 form conductive leads for connecting the ends of the filamentary cathode to an appropriate source of electrical energy. For this purpose, the side rods 30 and 32 are connected through the glass press 12 respectively to two of the base pins 15. The surface of the corrugated filament ribbon 26 is coated with an electron emissive material such as a mixture of the oxides of barium and strontium to provide a source of electron emission within the tube.

Surrounding the cathode structure 26 is a cylindrical metal heat shield 38 spaced therefrom. The heat shield 38 is mounted coaxial with the circular anode electrode 16. The bottom of the cylindrical shield 38 is closed by a circular metal plate structure 40 fixed at its periphery to the inner surface of the lower end of cylinder 38. Bottom plate 40 is apertured to permit the passage therethrough of the cathode support rods 30 and 32. A rod 42 sealed in the glass stem 12 extends upwardly to support the shield plate 40 at its center. A metal washer 45 fixed to both the rod 42 and the plate 40 provides a rigid brace for the heat shield 38. Likewise, a similar metal washer 44 fixed to the side rod 30 and secured in abutment to the bottom of plate 40 forms an additional rigid support for the heat shield 38. Through washer 44 shield 38 is electrically tied to the end 34 of the filamentary cathode. This places the heat shield 38 at the same potential as the terminal end 34 of the cathode 26. The other cathode support rod 32 is insulated from plate 40 by the insertion of a ceramic washer 46.

The upper end of the heat shield 38 is partially closed by an annular plate element 48 whose periphery is fixed to the inner surface of the cylinder 38. The plate 48 has an opening or aperture 50 which is coaxial with both the circular anode plate 16 and the cylindrical heat shield 38. The aperture 50 of the end plate 48 provides a path for the passage of a discharge between the filamentary cathode 26 and the anode electrode 16.

The purpose of the closed heat shield 38 is to prevent the dissipation of heat energy from the filamentary cathode and results in less electrical energy being required to raise the temperature of the cathode to the desired point for electron emission. A second apertured plate 52 may be fixed to the inner surface of the end shield plate 48 to provide greater heat insulation. Furthermore, the heat shield 38 is tied electrically to the cathode potential so that theoretically the shield will have a neutral effect upon the electron discharge from the cathode 26.

Between the filamentary cathode 26 and the anode electrode 16 is mounted a control electrode or grid structure 54. The grid electrode 54 includes a tubular portion 56 extending downwards coaxial with the anode plate 16 and aperture 50 in the shield plate 48. The grid structure 54 is mounted on a cylindrical portion 58 extending coaxial to the sides of the glass envelope 10. Fixing this grid cylinder 58 within the tube are channel bar side rods 60 which extend adjacent to the stem 12. Mounting the supporting side rods 60 on the stem tubulation 12 are additional rod supports 62 held rigidly to the stem 12 by a screw type clamp means 63. The control grid plate 54 and the tubular portion 56 are preferably made of heavy copper material so as to provide high heat conductivity from the region of the tubular portion 56 to cylindrical grid portion 58. This grid structure 58 operates as a radiator or heat dissipating means for lowering the operative temperature of the control grid. To further increase the radiating surface of the grid cylinder 58, it is preferably coated with powdered zirconium metal sintered to the metal surface of cylinder 58. With this arrangement, the heat encountered in the region of the arc discharge within the tubular portion 56 is effectively connected to the radiating cylinder 58 and appropriately dissipated. This means permits the control grid 54 to operate at a lower temperature and helps to eliminate the undesirable effects of grid emission. Spring centering clips 64 are fixed to side rods 60 to keep the grid structure properly spaced from the side walls of the tube envelope.

Fig. 3 illustrates an application of this type of control tube and also shows one manner in which the tube parts are connected in an operative circuit. In this figure, the gas control tube 10 is used to operate a relay, for example, at a predetermined time when there is a scheduled change of grid potential. A source of electrical energy including, for example, a plate circuit transformer 70 provides an alternating potential to circuit lines 72 and 74. Anode plate 16 of the control tube 10 is connected directly to circuit line 72 through a load or relay 75. The filamentary cathode 26 of tube 10 is heated by a current derived from the secondary 80 of a filament transformer 78. The primary coil 76 of transformer 78 is connected across the circuit lines 72 and 74. Also, the filamentary cathode 26 is connected into the alternating circuit by a lead

85 joining the center tap of the filament transformer coil 88 with a terminal point 84. The terminal point 84 is separated from circuit line 72 by a large resistance 82 and from circuit line 74 by a much smaller resistance 83. This arrangement produces a greater IR drop between terminal point 84 and circuit line 72 than between terminal point 84 and line 74. Control grid 54 of the control tube 10 is connected through a grid resistance 96 and an adjustable contact 98 to resistance 83. A phototube 90 has its anode electrode 92 joined to circuit line 72 and the photocathode 94 connected directly to the grid circuit.

This circuit arrangement produces a difference of potential between the anode 16 of tube 10 and the filamentary cathode 26. When the anode 16 is positive during the one-half cycle of voltage alternation, the control electrode 54 is at a lower negative voltage potential than the cathode 26. The contact 98 in the grid circuit may be varied to maintain a sufficiently negative potential on grid 54 to prevent any electron discharge between the negative cathode 26 and the positive anode plate 16. When there is an activation of the photocathode 94 of phototube 90, the electron emission from the photocathode 94 will cause a shift of the potential on the control grid 54 of tube 10 in the positive direction. Adjustments may be made so that this positive shift in the grid potential produced by the photocathode will permit an electron discharge to take place between grid 54 and the anode plate 16. The electron discharge ionizes the gas in the well known manner so that the primary emission from the cathode 26 is greatly amplified. This reaction results in a current being conducted through the control tube 10 to operate relay 75.

The operation of the grid controlled gas tube 10 is such that the tube will conduct during all of the half cycle when the anode is positive, if there is no negative charge on the control grid. If the control grid is maintained at a certain negative value, no discharge will take place through the tube during the half cycle the anode is positive until the voltage drop between the anode and cathode has built up to a critical value. At this value, the restraining field of the negative control electrode is overcome and the tube will break down and conduct for the rest of the half cycle. The tube discharge cannot be stopped by the control grid once it has started. However, removal of the positive anode potential at the end of the half cycle stops tube discharge.

If a potential more negative than a determinable critical value is applied to the control grid, no discharge will take place through the tube under normal operating conditions. In usual practice a bias potential is placed on the control grid more negative than the critical value to prevent the tube from discharging. If the grid potential is shifted to a point in the positive direction above the critical value by any means such as the phototube 90 of Fig. 3, the control tube will conduct when the potential difference between the anode and cathode electrodes reaches a corresponding breakdown value.

In gas-filled and mercury vapor thyratrons of the type similar to that disclosed in Figs. 1 and 3, there are large changes in starting voltage characteristic. Since the heat shield 38 of tube 10 is electrically connected to one end 34 of the cathode filament 26, the heat shield varies from a positive maximum to a negative maximum and back, as the A.-C. filament voltage varies through

one cycle. Furthermore, the shield 38, during this voltage cycle, is actually at a different potential from the other end 36 of the filamentary cathode and also from any other part of the cathode filament. Also, the midpoint of the cathode filament is at the same potential as the filament transformer center tap 86, and is the voltage reference for the grid and anode.

The potential difference between the heat shield 38 and the cathode filament varies with the change in phase relationship between the anode voltage and the filament voltage. When the potential of heat shield 38 is in phase with the anode voltage, that is, positive when the anode is positive, then shield 38 is more positive than the emitting portions of the cathode filament. If the shield is out of phase with the anode voltage by 180° or negative when the anode is positive then the heat shield is more negative than the emitting portions of the cathode filament. The results of such a relationship is that the heat shield aperture 50 exerts a "grid-action" during tube operation in a manner to vary the anode starting voltage relative to phase difference between the A-C. anode voltage and the A-C. filament heat shield voltage.

Fig. 4 discloses graphically the relationship between the grid bias voltage and the anode starting voltage or tube starting characteristic relative to the difference in phase relationship between the A-C. anode voltage and the A-C. filament heat shield voltage. Curve A represents the starting characteristic of the tube when the phase difference is 180° and curve B when the phase difference is 0°. Any similar curve between A and B would represent the tube starting characteristic when the phase difference is between 0° and 180°. It is evident from Fig. 4 that at high anode starting voltages the change in the tube starting characteristic is larger for a given variation in phase relationship than at low anode starting voltages.

To minimize this "grid action" of heat shield aperture 50 and to produce a more constant tube starting characteristic, I have devised a novel type of shield electrode. In Figs. 1 and 2, this shield electrode consists of a metal ring 100 positioned directly below the heat shield aperture 50. The ring 100 is mounted on an extension of the support rod 32. As shown in Fig. 1, the form of the shield electrode comprises an extension of the support rod 32 to a point below the shield plate 48 where it is bent to form a horizontal part. This horizontal part forms the closed ring 100 positioned coaxially with the opening 50 in the shield plate 48. The opening through the shield ring 100 is preferably the same size as the shield aperture 50. Since the ring 100 is integral with the support rod 32 it is maintained at the same electrical potential as end 36 of the cathode filament. The ring 100 and the support rod 32 are insulated from the heat shield 38 by the ceramic washer 46. With this arrangement, the ring 100 will always have an equal and opposite electrical potential to that of the heat shield 38. This results in producing a neutralizing effect on the heat shield aperture 50. The changing electrostatic field maintained by the A-C. voltage of the neutralizing ring 100 counteracts the electrostatic field produced by the grid action of aperture 50.

Fig. 4 shows by curves C and D the results produced by use of neutralizing ring 100. C represents the tube starting characteristic when the phase difference between the A-C. anode

voltage and the A-C. filament-heat shield voltage equals 180°. The curve D represents the tube starting characteristic when the phase difference is 0°. It is evident that the effects of the phase difference has been considerably lessened by the use of the neutralizing ring. However, at high anode starting voltages, the change in tube starting characteristic for a given variation in phase relationship is still large, but from Fig. 4 it can be seen that at low anode starting voltages the maximum variation in starting voltage through a full 180° phase anode is small.

I have found that in a tube of the type shown in Fig. 1 which uses a neutralizing electrostatic shield similar to ring 100, the maximum variation in the starting voltage through a full phase shift of the filament voltage is in the order of three volts. Tubes of the same design without the neutralizing ring have variations in the order of 60 to 100 volts under identical operating conditions.

It is not necessary to be confined to the particular type of neutralizing shield 100 disclosed in Fig. 1. The desired effectiveness of the ring shield 100 may be varied by changing its dimensions and its position. For example, in Fig. 5 the neutralizing electrode 105 is in the form of a short tubular structure 104. In Fig. 6, the neutralizing electrode is represented as an apertured disc with an opening 106 coaxial with aperture 50 in heat shield 48. It may be found desirable to make the aperture of the neutralizing electrode either smaller or larger than the heat shield aperture 50. As shown in Fig. 6, aperture 106 is represented as being smaller than the opening 50.

In Fig. 7, a heat shield 108 is represented as enclosing the filamentary cathode 26. Shield 108 is of a cone-shaped configuration with an aperture 109 at its apex. In this case, the neutralizing ring 110 also takes the same configuration as the heat shield and has its wall spaced in a parallel arrangement to those of the heat shield 108. The configurations of the heat shield and that of its corresponding neutralizing ring are not limiting and either may be modified in any way desirable to produce a neutralizing effect upon the "grid action" of the heat shield aperture. If the apertured portion of the heat shield comprises a plurality of openings the neutralizing electrode may take the form of a plate 112 having a plurality of openings 114 in a corresponding relationship to the openings in the heat shield. Furthermore, essentially the same results may be produced by placing the neutralizing electrode immediately above the heat shield opening 50. However, in this case, the problem of insulating the neutralizing electrode from the heat shield 38 may be greater.

While certain specific embodiments have been illustrated and described, it will be understood that various changes and modifications may be made therein without departing from the spirit and scope of the invention.

What I claim as new is:

1. An electron discharge device comprising a sealed envelope, an anode electrode mounted within said envelope, a cathode electrode spaced within said envelope from said anode electrode, said cathode having an electrical resistance between two portions thereof, means connected to said portions for supplying a heating current to said cathode, a shield spaced within said envelope between said anode and cathode electrodes, said shield having an aperture for the passage

7 of a discharge between said anode and cathode electrodes, means electrically connecting said shield to one of said cathode portions, an electrostatic shield means mounted between said cathode electrode and said heat shield in the path of the discharge, said electrostatic shield means connected to the other one of said cathode portions to electrostatically neutralize said apertured heat shield.

2. An electron discharge device comprising a sealed envelope, an anode electrode mounted within said envelope, a cathode electrode spaced within said envelope from said anode electrode, said cathode electrode including a filament, a metal lead connected to each end of said filament for conducting a heating current thereto, a shield spaced within said envelope from said cathode electrode and including a portion extending between said anode and cathode electrodes, said shield portion having an aperture for the passage of a discharge between said anode and cathode electrodes, means electrically connecting said shield to one of said metal leads, a shield electrode mounted in the path of said discharge and between said cathode electrode and said shield portion, said shield electrode connected to the other one of said metal leads to electrostatically neutralize said apertured shield portion.

3. An electron discharge device comprising a sealed envelope, a gaseous medium within said envelope, an anode electrode mounted within said envelope, a filamentary cathode electrode spaced within said envelope from said anode electrode, a conductor lead connected to each end of said filamentary cathode for supplying a heating current thereto, a heat shield within said envelope spaced from and enclosing said cathode, said heat shield having an apertured plate portion for the passage of an arc discharge between said anode and cathode electrodes, said heat shield electrically connected to one of said conductor leads, a foraminous shield electrode mounted between said cathode electrode and said apertured plate portion in the path of said arc discharge, said shield electrode connected to the other of said conductor leads to electrostatically neutralize said apertured plate portion.

4. An electron discharge device comprising a sealed envelope, a gaseous medium within said envelope, an anode electrode mounted within said envelope, a cathode electrode including a filament and a coating of high electron emissivity fixed to said filament surface to provide a source of electron emission, means connected to the ends of said filament for supplying a heating current thereto, a tubular heat shield within said envelope spaced from and enclosing said cathode, an annular plate closing one end of said heat shield for the passage of an arc discharge between said anode and cathode electrodes, means electrically connecting said annular plate to one end of said cathode filament, an electrostatic shield electrode having an aperture axially aligned with said annular plate and positioned between said cathode filament and said annular plate, means electrically connecting said electrostatic shield electrode to the other end of said cathode filament whereby electrostatic effects of said annular plate upon the electron emission from said cathode are neutralized.

5. An electron discharge device comprising a sealed envelope, a gaseous medium within said envelope, an anode electrode mounted within said

5 envelope, a cathode filament including an electron emissive coating, means connected to the ends of said filament to supply a heating current thereto, a closed cylindrical heat shield within said envelope spaced from and enclosing said cathode filament, one end of said cylindrical heat shield having a circular opening therethrough for the passage of an arc discharge between said anode and cathode electrodes, means electrically connecting said heat shield to one end of said cathode filament, an electrostatic shield electrode mounted within said heat shield, said electrostatic shield including an apertured disc axially aligned with said circular opening, means electrically connecting said electrostatic shield to the other end of said cathode filament whereby any electrostatic effects of said circular opening upon the electron emission from said cathode are neutralized by said apertured disc.

6. An electron discharge device comprising a sealed envelope, a gaseous medium within said envelope, an anode electrode mounted within said envelope, a cathode electrode spaced within said envelope from said anode electrode, a grid electrode mounted between said anode and cathode electrodes for controlling the initiation of an arc discharge therebetween, said cathode electrode including a filament and an electron emissive coating on said filament surface, means for connecting the ends of said cathode filament to a source of alternating current, a cylindrical heat shield axially aligned with said anode and control electrodes and enclosing said cathode electrode, a plate structure closing the end of said cylindrical shield between said cathode and grid control electrodes, said plate structure having a circular aperture coaxial with said cylindrical shield for the passage of an arc discharge between said anode and cathode electrodes, means electrically connecting said heat shield to one end of said cathode filament, an electrostatic shield mounted within said cylindrical shield, said electrostatic shield including a metal ring coaxially spaced between said circular aperture and said cathode filament, means electrically connecting said electrostatic shield ring to the other end of said cathode filament to neutralize the electrostatic effects of said circular aperture upon cathode emission whereby the loss of grid electrode control is prevented.

7. An electron discharge device having an envelope containing a gaseous atmosphere, an anode electrode within said envelope, an elongated cathode within said envelope, a conducting shield surrounding said cathode, said shield having an aperture therein through which a discharge can occur between said cathode and said anode, one end of said cathode being connected to said shield, an electrostatic shielding means adjacent said aperture, said electrostatic shielding means being connected to the other end of said cathode.

8. An electron discharge device having an envelope containing a gaseous atmosphere, an anode electrode within said envelope, a cathode filament within said envelope, a metallic shield surrounding said cathode for shielding said cathode, said shield having an aperture therein through which a discharge can occur between said cathode and said anode, one end of said cathode being connected to said shield, an electrostatic shielding means within said shield adjacent said aperture, said electrostatic shielding means being connected to the other end of said cathode.

9. An electron discharge device having an envelope containing a gaseous medium, a cathode

within said envelope and an anode, said cathode including a filament, a heat shield surrounding said filament and having an aperture through which a gas discharge can take place, one side of said filament being connected to said heat shield, and an electrostatic shield within said heat shield adjacent said aperture and connected to the other end of said filament.

10. An electron discharge device having an envelope containing a gaseous medium, a cathode within said envelope and an anode, said cathode including a filament, a heat shield surrounding said filament and having an aperture through

which a gas discharge can take place between said anode and cathode electrodes, a grid electrode mounted between said anode electrode and heat shield for controlling the initiation of the gas discharge through said aperture, one side of said filament being connected to said heat shield, and an electrostatic shield within said heat shield adjacent said aperture and connected to the other end of said filament, to neutralize the electrostatic effects of said shield aperture upon tube discharge whereby loss of grid electrode control is prevented.

CHARLES P. SMITH.
